(57) **CLAIM**

The ornamental design for a portable blowing machine hood having a feeder tray for blowing loose fill, as shown and described.

DESCRIPTION

FIG. 1: is a front, right side perspective view of the blowing machine hood according to our design;

FIG. 2: is a rear, right side perspective view thereof;

FIG. 3: is a rear plan view thereof;

FIG. 4: is a right side plan view thereof;

FIG. 5: is a front, left side perspective view thereof;

FIG. 6: is a bottom plan view thereof; and,

FIG. 7: is a top left side perspective view thereof.

The broken lines showing the knife slot for cutting packaged bags of loose fill insulation and a left side viewing window form no part of the claimed design.
